UNITED STATES PATENT OFFICE.

WILLIAM A. MITCHELL, OF DENISON, TEXAS, ASSIGNOR TO UNIVERSAL DRAFT GEAR ATTACHMENT CO., OF CHICAGO, ILLINOIS, A CORPORATION OF ILLINOIS.

RAILWAY TRUCK.

Application filed August 1, 1924. Serial No. 729,440.

This invention relates to improvements in trucks for railway cars.

One of the objects of the invention is the provision of new and improved means for retaining in proper position the columns of railway trucks of the arch bar type which, through use, have become deranged or displaced.

Another object of the invention is the provision of a new and improved brake supporting bracket for a railway truck.

Other objects of the invention are the provision of a truck column retainer member or clip that is cheap to manufacture, simple in construction, easily assembled in position on the truck, and when assembled will hold the corresponding column rigidly in position.

Other and further objects and advantages of the invention will appear from the following description taken in connection with the accompanying drawings, in which—

Fig. 1 is a side elevation of a truck of a railway car, with parts broken away;

Fig. 2 is a section on line 2—2 of Fig. 1;

Fig. 3 is a section on line 3—3 of Fig. 1;

Fig. 4 is a top plan view of the device shown in Fig. 3 with the head of the bolt removed;

Fig. 5 is a detail of the filler member;

Fig. 6 is a side elevation of a portion of a railway truck showing my invention in position thereon;

Fig. 7 is a plan view of the same;

Fig. 8 is a section on line 8—8 of Fig. 6, with parts broken away; and

Fig. 9 is a side elevation at right angles to that shown in Fig. 8.

In the present construction of railway trucks of the arch bar type, the continual movement of the bolster relatively to the guiding columns and the strains and stresses between the same often results in breaking and spreading the upper ends of the columns, which necessitates replacing the mutilated columns with new ones at considerable expense. Furthermore, it is not uncommon for the brake supporting eyes on the truck columns to become broken off thus necessitating the substitution of new columns at a considerable expenditure of time and labor. My invention contemplates the provision of simple and inexpensive means that will avoid the necessity of sub-

stituting new columns for the mutilated or displaced ones.

On the drawing the reference character 10 designates a truck for a railway car comprising the upper and lower arch bars 11 and 12, respectively, the columns 13 interposed between the arch bars, a bolster 14 vertically movable between said columns and guided thereby, springs 15 for supporting said bolster and bolts 16 for holding the parts in assembled relation, all of which are of the usual or of any well known construction. The upper and lower arch bars 11 and 12, the columns 13 and bolts 16 may be considered as forming a truss for supporting the bolster 14 for carrying the same by the wheels 5. The columns 13 are provided with brackets or lugs 8 to which the brake supporting links 9 are adapted to be pivotally attached, and with grooves facing inwardly for receiving the bolts 16. The upper ends of the columns 13 are provided with flanges 17 extending upwardly at each side of the upper arch bar 11, see Figs. 1 and 2, for preventing lateral movement of said columns.

The rough usage to which railway trucks are subjected in the sudden starting, stopping and bumping of the cars often results in spreading apart the top ends of the columns. It has been proposed to employ tie bars extending from one column to the other to remedy this defect, but the use of these devices necessitates the insertion of the tie bars between the top arch bar and the columns, which is objectionable because it not only spreads the arch bars apart but raises the upper arch bar 11 out of the channels formed by the flanges 17, thereby depriving the top arch bar of its necessary lateral support.

Suitable means are provided for holding the columns 13 in position which does not possess the objectionable features noted above. In the form of the device selected to illustrate one embodiment of the invention a clip or anchoring device is provided for each column and the parts are so constructed that when in position the columns are securely held within the recess or channel formed by the flanges 17. As shown in Figs. 1 to 4, the anchoring device or clip comprises a body portion 18 having flanges 19 adapted to extend down-

wardly at each side of the top arch bar 11, and a loop 20 depending from the outer end of the body portion through which said arch bar is adapted to extend. The body portion is provided with an aperture 21 through which the bolt 16 is adapted to extend for holding the anchoring device in position. The depending loop 20 engages in rear of the corresponding column thus preventing the upper end of the same from moving away from the bolster 14.

In applying the device to a truck in which the columns have become distorted or spread apart, the top arch bar is unfastened, the bolts 16 removed, the columns are straightened or placed in normal position, and the anchoring devices are threaded on the top arch bar. The bolts 16 are replaced through the aligned openings in the anchoring devices and arch bars and the parts secured in position in the usual manner. The clip or anchoring device forms a washer for the bolt 16. The top of the body portion 18 may be, and preferably is, provided with an upwardly extending lug 20 for engaging one side of the head of the bolt 16 to prevent the same from turning.

The opening 21 in the body portion is preferably elongated whereby the same is adapted to be employed in connection with columns of different widths. A crescent-shaped filler block 23 is adapted to occupy that portion of the opening 21, not occupied by the bolt 16. If, for instance, the clip be employed on a truck having a column of less width than that shown in Figs. 1 to 4, the filler member 23 will be on the opposite side of the bolt from that shown in Fig. 4.

Not infrequently the brake supporting bracket on the column gets broken off. Formerly, in order to repair the truck, it was necessary to replace the broken column at considerable time and expense. In Figs. 6 to 9 inclusive is shown a modified form of the anchoring device or clip that is provided with a brake supporting bracket. With the use of this device, when the bracket is broken off it is only necessary to apply an anchoring device with a brake supporting bracket and reassemble the parts without removing or replacing the column.

As shown in Figs. 6 to 9 inclusive, the anchoring device or clip 25 is constructed similar to the clip shown in Figs. 1 to 5, except that it is provided with a depending angular flange 26 which is so constructed that the sides 27 and 28 of said flange will conform to and engage two adjacent sides of the column 13. The side 28 of the depending flange is provided with a bracket 31 having the two spaced lugs

32 between which the brake supporting link 33 is adapted to be pivoted. The parts are so constructed that when the clip or anchoring device is in position on the truck, the bracket 31 will occupy substantially the same position as the corresponding brackets 8 in Fig. 1, whereby the brake 34 will occupy its normal position.

In practice, if the columns 13 spread apart and the brake supporting bracket 8 is intact, the columns are straightened and the clips or anchoring devices shown in Fig. 1 are employed. If, on the other hand, the brake supporting bracket is broken off the clip or anchoring device 25 shown in Figs. 6 to 9 is employed.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. As an article of manufacture, an anchoring member for bracing a column of a truck frame of the arch bar type, comprising a body portion having a vertical opening therein and provided with depending portions spaced apart for engaging the side edges of an arch bar of a truck and adapted to form by contact only a stop for said column.

2. In a railway truck of the arch bar type, the combination of a pair of bars spaced apart between their ends, a pair of supporting columns between said bars, means for securing said columns in position between said bars, said means comprising a bolt for each column, said bolts extending through both of said bars, and a brake hanger clip detachably secured to said truck frame by one only of said bolts, said clip being provided with a brake hanger bracket for supporting the brake mechanism.

3. In a railway truck of the arch bar type, the combination with a supporting column, of a retaining bolt associated with said column and extending through the bars forming said arch, and an anchoring member secured to said bolt and providing a washer for one end thereof, said member having an integral portion adapted to prevent movement of said column outwardly in the plane of said arch.

4. As an article of manufacture, an anchoring member for railway truck columns, said member having a portion for connection to the retaining bolt and arch bar of said truck, and a portion for supporting said column, and a brake supporting bracket depending from said member.

5. An anchoring device for railway truck columns comprising a body portion having an aperture therethrough and a depending loop portion for engaging the upper arch 5 bar of a railway truck.
6. An anchoring device comprising a body portion adapted to be secured to a railway truck, means on said body portion for engaging the arch columns for holding the 10 same in operative position, and a brake supporting bracket secured to the body portion.
7. An anchoring device for retaining a truck column in operative position, comprising a body portion having downwardly extending integral flanges forming a recess for engaging the top and side edges of the upper arch bar of a truck, said body portion provided with an opening for engaging one 15 only of the column-holding bolts of said truck and integral means on said body portion for engaging one face of said column for preventing said column from moving relatively to said bolt.
- 20 8. In a railway truck of the arch bar type, the combination of a supporting column, an anchoring device for holding said column in operative position, and a brake supporting bracket on said anchoring device.
9. In a railway truck, opposed arch bars, a pair of opposed truck columns provided with grooves on each end for engaging said bars, bolts for holding said columns in 25 spaced relation between said bars, a pair of clips provided with elongated openings for engaging said bolts outwardly of said bars and having shoulders for engaging said columns, filler members in said openings for engaging said bolts, and means on said clips 30 for preventing said bolts from turning.
10. In a railway truck, opposed arch bars, a pair of truck columns provided with grooves in the upper ends thereof, means extending through said bars for holding said 35 columns between said bars in spaced relation and with said bars in said grooves, and means engaging said first named means for forming an abutment to prevent spreading 40 of said columns.
11. A substitute brake hanger for a conventional railway truck frame of the arch bar type comprising a body portion having one end bent at an angle and provided with a single opening through which an attaching member forming a part of said frame is adapted to extend for detachably securing said hanger to said truck frame, and a depending member having means at its free 45 end whereby the usual brake hanger link 50 may be pivotally connected thereto.
12. In a railway truck of the arch bar type, the combination of a pair of bars spaced apart between their ends, a pair of supporting columns between said bars, bolts 55 extending through said bars for securing said columns in spaced relation between said bars, brake mechanism for said truck, a brake hanger clip provided with a brake 60 hanger bracket for supporting said brake 65 mechanism, and having its upper end bent to engage the upper surface of said truck, and provided with a single aperture for receiving one only of said bolts for rigidly securing said clip to said truck with said 70 bracket adjacent to and extending downwardly along one of said columns.

WILLIAM A. MITCHELL.
